UNITED STATES PATENT OFFICE

ADOLPH L. NELSON, OF DETROIT, MICHIGAN, ASSIGNOR TO BOHN ALUMINUM & BRASS CORPORATION, OF DETROIT, MICHIGAN

PISTON

Application filed November 5, 1927, Serial No. 231,170. Renewed January 17, 1929.

This invention relates to pistons, and particularly to pistons adapted for use in internal combustion engines.

The invention aims to provide a piston in which the lower end of the skirt will be somewhat yielding but will be strong enough to operate successfully under long periods of use.

The piston formation of this invention is particularly useful in connection with a piston formed of light-weight material in which the thermal expansion of the thrust-bearing portions is controlled by struts of relatively in-expansive material. According to this invention the lower end of the skirt is slotted in such a way as to render it responsive to the influence of the control member and yet retain a certain required amount of stiffness.

While preferred embodiments have been illustrated for purposes of illustration, it should be understood that various changes may be made in the structure without departing from the spirit and scope of the invention as hereinafter set forth and claimed.

In the drawings; Fig. 1 is an elevation partly in section of a piston embodying the invention.

Fig. 2 is a section on line 2-2 of Fig. 1.

Fig. 3 is an elevation of a modified form.

Fig. 4 is a section showing a still further modification.

Referring to the drawings more particularly, the reference character 10 indicates the head of the piston, while characters 11 indicate piers depending from the head and having piston pin bosses 12 formed therein. The lower end of the skirt constitutes an annular portion 13 which is connected to the lower end of the piers 11 through horizontal arcuate webs 11^a. Tongues 14 and 14^a extend upwardly from the annular portion 13 between the piers, and the upper ends of the tongues are spaced from the head by slots 15, and from the piers by the vertical openings 16.

The parts already described are preferably formed of some suitable light-weight material such as aluminum alloy, and in order to control the expansion of the upper ends of the tongues 14 and 14^a, a pair of struts 17 of some material less expansible than the piston ma-

terial are placed across the piston with their ends engaging the tongues 14 and 14^a. The intermediate portion of each strut is embedded in one of the piers 11 as will be clear from Fig. 1.

It is desirable to form the lower end of the skirt in such a manner that it will be somewhat yielding and still retain sufficient stiffness to withstand the strains of piston operation. In the present instance these results are obtained by a suitable combination of a slot or slots extending upwardly from the lower end of the skirt together with slots extending into the skirt from the lower end of the vertical openings 16.

In the piston illustration in Figs. 1 and 2 a slot 18 extends upwardly into the tongues 14, and short slots 19 extend into the skirt from the lower ends of the vertical openings 16 adjacent tongue 14. The slots 19 may be formed at any desired angle, and the slots 18 and 19 may be suitably varied in length. It will be evident that varying degrees and arrangements of skirt stiffness may be obtained by varying the lengths and positions of the slots 18 and 19.

In certain cases the best operating results may be obtained by forming the tongue 14^a as well as the tongue 14 with slots 18 and 19, as illustrated in Fig. 4.

Fig. 3 shows how the slots 19 can be combined with a plurality of short slots 20. In this case the stiffness of the skirt is partly determined by the distance between the upper end of slot 20 and the opening 16 as well as by the distance between the upper end of slot 20 and the lower end of slot 19. The tongue 14^a can also be slotted in this manner.

I claim:

1. A piston comprising a head, piers depending from the head, a skirt connected to the lower ends of the piers, said skirt including a lower annular portion and tongues extending upwardly from the annular portion, the tongues being separated from the piers by openings, the skirt being formed with a slot extending into the skirt from the lower end of one of the openings, and one of the tongues being formed with a slot ex-

tending upwardly from the lower edge of the skirt.

2. A piston comprising a head, piers depending from the head, a skirt connected to the lower ends of the piers, said skirt including a lower annular portion and tongues extending upwardly from the annular portion, the tongues being separated from the piers by openings, the skirt being formed with slots extending into the skirt from the lower end of two of the openings, and one of the tongues being formed with a slot extending upwardly from the lower edge of the skirt.
- 10 3. A piston comprising a head, piers depending from the head, a skirt connected to the lower ends of the piers, said skirt including a lower annular portion and tongues extending upwardly from the annular portion, the tongues being separated from the piers by openings, one of the tongues being formed with a slot extending upwardly from the bottom of the skirt, and the skirt being formed with a slot extending into the skirt from the lower end of each of the openings adjacent the slotted tongue.

4. A piston of light weight material comprising a head, piers depending from the head, a skirt connected to the lower ends of the piers, said skirt including a lower annular portion and tongues extending upwardly from the annular portion on opposite sides of the piston, the tongues being separated from the head by slots and from the piers by openings, struts of relatively in-expansible material connecting the upper ends of the tongues, one of the tongues being formed with a slot extending upwardly from the bottom of the skirt, and the skirt being formed with a slot extending into the skirt from the lower end of each of the openings adjacent the slotted tongue.

5. A piston of light weight material comprising a head, piers depending from the head, a skirt connected to the lower ends of the piers, said skirt including a lower annular portion and tongues extending upwardly from the annular portion on opposite sides of the piston, the tongues being separated from the head by slots and from the piers by openings, struts of relatively in-expansible material connecting the upper ends of the tongues, each of the tongues being formed with a slot extending upwardly from the bottom of the skirt, and the skirt being formed with a slot extending into the skirt from the lower end of each opening.

6. A piston of light weight material comprising a head, piers depending from the head, a skirt connected to the lower ends of the piers, said skirt including a lower annular portion and tongues extending upwardly from the annular portion on opposite sides of the piston, the tongues being separated from the head by slots and from the piers by

openings, struts of relatively in-expansible material connecting the upper ends of the tongues, one of the tongues being formed with a plurality of slots extending upwardly from the bottom of the skirt, the other tongue being unslotted, and the skirt being formed with a slot extending into the skirt from the lower end of each of the openings adjacent the slotted tongue.

7. A piston comprising a head, piers depending from the head, a skirt connected to the lower ends of the piers, said skirt including a lower annular portion and tongues extending upwardly from the annular portion, the tongues being separated from the piers by openings, the skirt being formed with a slot extending into the skirt from the lower end of one of the openings.

8. A piston of light weight material comprising a head, piers depending from the head, a skirt connected to the lower ends of the piers, said skirt including a lower annular portion and tongues extending upwardly from the annular portion on opposite sides of the piston, the tongues being separated from the head by slots and from the piers by openings, struts of relatively in-expansible material connecting the upper ends of the tongues, the skirt being formed with a slot extending into the skirt from the lower end of one of the openings.

In testimony whereof I affix my signature.
ADOLPH L. NELSON.
